UNITED STATES PATENT OFFICE.

WILLIAM F. PETERS, OF CINCINNATI, OHIO.

PERMUTATION-LOCK.

SPECIFICATION forming part of Letters Patent No. 412,977, dated October 15, 1889.
Application filed September 17, 1888. Serial No. 285,656. (Model.)

To all whom it may concern:

Be it known that I, WILLIAM F. PETERS, a citizen of the United States, and a resident of the city of Cincinnati, in the county of Hamilton and State of Ohio, have invented certain new and useful Improvements in Combination-Locks, of which the following is a specification.

The several features of my invention and the advantages arising from their use, con- 10 jointly or otherwise, will be apparent from the following description.

In the accompanying drawings, forming part of this specification, Figure 1 is a view of the dial-index of the lock. Fig. 2 is a view of the lock from the back, the disks being in position to accommodate the retracted bolt. Fig. 3 is a view similar to Fig. 2, but with the bolt in the position of locking. Fig. 4 is a view of 20 the interior of the lock from the back, the disks being removed. Fig. 5 is a view similar to Fig. 1, with the innermost disk removed. Fig. 6 is a view similar to Fig. 5, with the next disk removed. Fig. 7 is a central vertical section of 25 the lock. Fig. 8 is a view of the innermost disk. Fig. 9 illustrates one of the rings separating the disks.

The lock is particularly adapted for application to drawers, but may be used for other 30 purposes—as safes, for instance.

The box A, containing the operative parts of the lock, is set in the frame C of the drawer or safe or other article to which the lock is to be applied. The drum A' projects inwardly 35 from the outer face a of the box A. At its base it is provided with the shoulder a', which forms the bearing for the outermost disk. It is also provided with the groove a², running lengthwise. Each disk D is provided with a notch d 40 in the edge to receive the projecting arm g² of the bolt-frame. Each disk is also provided with a lug d', extending toward each adjacent disk. The number of disks employed in the lock is immaterial. The innermost disk B 45 differs from the other disks in the combination. The disks D are mounted on the drum A', and are separated from each other by the rings E. Each ring E is provided with a lug e, which is received in the groove a² of the drum A', and is in this way prevented from turning. The disk B is provided, like the disk D,

with a lug b, projecting from its outer face to engage with the lug d' of the adjacent disk. The notch b³ in its edge has one sloping side, which serves as an inclined plane to raise the 55 arm g² of the bolt-frame from the notches d of the outer disks. The disk B is also provided with the central hub b', which is received within the drum A'. The face of the hub b' is provided with a series of radial 60 grooves b². The dial F is provided with the stem f, which passes through the outer frame C and is received in the drum A'. The end of the stem f is provided with a lug f', which projects slightly from the surface and extends diametrically across the end of the 65 stem. The lug f' is adapted to be received in any of the grooves b² in the hub b' of the disk B. The stem f and the disk B are clamped together by the screw G². To change the relative positions of the dial and the disk B, and in this way to change the combination, it is only necessary to loosen the screw G³ and turn the dial until the lug f' slips into a different groove b² from what it was in before. In this 70 way as many different combinations can be made as there are radial grooves b². The bolt G is rigidly attached to the frame G', the two being preferably made in one piece. The frame G' is provided with the slots g, through 75 which the pins g' pass, and are screwed or otherwise secured to the box A. The frame and pins serve as a guide for the bolt. The arm g² extends from the frame G' or bolt over the disks. The spring H, fastened at one side of 80 the box A, presses the bolt toward the disks.

The mode of operation of the device is readily understood from its construction. When by means of the dial the disks are so set that the notches in their edges come into line, the 85 spring H forces the arm g² into the notches, and in this way retracts the bolt. To throw out the bolt, the dial is turned so that the inclined side of the notch b³ of the disk slides under the arm g², which is thus raised, and rests on the 90 circumferences of the disks, which keep the bolt out and the drawer or other article to which the lock is attached locked.

What I claim as new, and desire to secure by Letters Patent, is—

1. In a combination-lock, the combination of the dial-stem f, having at its end the lug

f', and the tumbler-disk B, having hub *b'*, provided with grooves *b²*, the lug *f'*, engaging any one of the said grooves at will, and screw *G²*, passing through tumbler B and screwed to 5 stem *f* and binding the same together, and having its head at the rear side of the tumbler B, substantially as and for the purposes specified.

2. In a combination-lock, the combination 10 of the stem-dial *f*, provided with end lug *f'*, and tumbler-disk B, having hub *b'*, carrying grooves *b²* for receiving the lug *f'*, securing screw *G²*, hollow sleeve or hub A', provided with shoulder *a'* and inclosing stem *f*, and hub 15 *b* of tumbler-disk B, and one or more tumblers

D, rotatable on sleeve A' and held from lateral displacement by the tumbler B and shoulder *a'*, substantially as and for the purposes specified.

3. The combination of the casing A, having 20 drum A', the bolt G, guide-frame G', arm *g²*, retracting-spring H, disk D, having notches *d*, disk B, having notch *b³*, and hub *b'*, having grooves *b²*, dial F, having stem *f*, provided with lug *f'*, and screw *G*, substantially as and 25 for the purposes specified.

WILLIAM F. PETERS.
